CLAIM

The ornamental design for a lighted automobile ceiling
console containing digital clock, compass and ther-
mometer, as shown.

DESCRIPTION

FIG. 1 is a left front perspective view of a lighted auto-
mobile ceiling console containing digital clock, compass
and thermometer showing my new design;

FIG. 2 is an enlarged left side elevation view thereof in
inverted condition;

FIG. 3 is an enlarged bottom plan view thereof;

FIG. 4 is an enlarged top plan view thereof;

FIG. 5 is an enlarged right side elevation view thereof
in inverted condition; and

FIG. 6 is an enlarged rear elevation view thereof in
inverted condition.

FIG. 1

FIG. 6

FIG. 4
